UNITED STATES PATENT OFFICE.

WILLIAM E. PEYTON, OF SHERMAN, OKLAHOMA.

COLLAPSIBLE EGG-CASE.

1,141,357.

Specification of Letters Patent.

Patented June 1, 1915.

Application filed March 11, 1914. Serial No. 823,998.

To all whom it may concern:

Be it known that I, WILLIAM E. PEYTON, a citizen of the United States, residing at Sherman, in the county of Major and State of Oklahoma, have invented certain new and useful Improvements in Collapsible Egg-Cases; and I do hereby declare the following to be a full, clear, and exact description of the invention, such as will enable others skilled in the art to which it appertains to make and use the same.

The primary object of this invention is to provide a strong, light, and simply constructed collapsible egg case or container, which may be easily and quickly collapsed to facilitate storage and transportation back to the point of shipment, and which may also be easily set up for packing.

Another and more specific object of the invention is to provide a case or container having side and end walls which are hingedly connected by corner fasteners and a removable bottom which, when in position, holds the walls in proper relation with respect to one another.

A further object of the invention is to provide in a case of this nature, a novel form of corner fastener or hinge which permits of the side and end walls folding into parallel spaced planes, so that the bottom, top, partition, and fillers may be arranged between these walls when the case is collapsed.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is a perspective view of the improved case, Fig. 2 is a perspective view of the case collapsed, Fig. 3 is a fragmentary section taken on the plane of line 3—3 of Fig. 1, Fig. 4 is a horizontal sectional view through the case, Fig. 5 is an end elevation, Fig. 6 is a detail perspective view of the cover looking against the upper side thereof, Fig. 7 is a detail view of one of the corner fastenings, and Figs. 8 and 9 are perspective views of supporting plates for the bottom.

Referring in detail to the drawings by numerals, 1 and 2 designate, as entireties, the side walls of the case and 3 and 4 the end walls thereof. The side walls are formed by skeleton frames having horizontal upper and lower bars 5 and 6, and uprights 7 which connect the longitudinal or horizontal bars. The end walls include skeleton frames formed by upper and lower bars 8 and 9 respectively and uprights 10. The inner sides of each of the frames of the side walls are lined with corrugated paper 11 or other suitable material. The end bars 8 and 9 are somewhat wider than the side bars 5 and 6 and have their outer longitudinal edges notched adjacent the terminals thereof, as indicated by the numeral 12 to receive the ends of the side bars. These notches are somewhat longer than the side bars are wide, which permits of the walls folding, as will be hereinafter described. The corners of the case, or more properly the corners of the side walls, are hingedly connected to one another by means of U-shaped fastening rods 13. One rod is provided for each corner of the case and has its arm portions extended inwardly through the side and end bars, as clearly shown in Fig. 1. The terminal of one of the arm portions of the fasteners may be bent against the inner longitudinal edges of the bars to secure the fasteners in place. It will be noted that the central portion of the fasteners extend diagonally across the corners of the case and that the terminals of the side and end bars are notched, as indicated by the numeral 15, to form seats for the central portion of the fasteners.

16 designates, as an entirety, the bottom of the case, which comprises a skeleton frame, having side bars 17, end bars 18, cross bars 19 paralleling the end bars, and a covering of corrugated paper 20, or some other suitable substance of light weight. To support the bottom within the case, I secure to the central portions of the end bars 9, plates 21. These plates are secured to the outer sides of the bars 9, extend under the lower edges thereof and under the end bars 18 of the bottom, as shown in Fig. 3, and have their inner edges turned to engage the inner sides of the bars 18. The bottom is further supported by angular plates 22 and 23 secured to the side walls of the case.

The plates 22 are connected to the longitudinal bars 6 and to the central uprights

7, and the plates 23 are bent around the bottom bars 6 and then extended inwardly to engage the lower faces of the bars 17 of the bottom 16.

5 The bottom fits accurately within the case and coöperates with the fasteners 13 to hold the walls of the case in proper relation to one another.

10 24 designates the lid or cover of the case that is removably secured in position with its upper surface flush with the upper edges of the side and end walls by means of spring catches designated 26 and 27. These spring catches are formed of flat strips of metal 15 and are slidable on the tops of the lid at points preferably central of the side edges and at the ends of the lid. Each of the catches comprises a flat strip of preferably spring metal that is bent at its inner end to 20 provide an upstanding flange and at its outer end to form an inwardly facing hook. Transverse bars 28 are mounted upon the upper surface of the lid 24 and have interposed between them and the lid 24, the 25 catches 26 and 27. The bars 28 have interposed therebetween and the lid or cover the catches 26 and 27. The inwardly facing hooks on the catches 26 and 27 engage crossed over plates 29 which bridge upwardly. 30 opening notches or recesses 30 formed in the end bars 8 centrally of their upper edges. The flanges on the inner ends of the spring catches engage the inner longitudinal edges of the bars 28 and it will thus be seen that the 35 lid is securely locked in position.

As a means for supporting the lid or cover prior to the securing of the catches 26 and 27 and for also strengthening the case generally I provide in connection with each bar 40 28 a pair of pivoted and short bars 31. These bars 31 are pivoted as at 32 each at one of its ends between the bars 28 and lid 24 at points adjacent the ends of the bars 28. It will thus be seen that the bars 31 when 45 in the position mentioned extend beyond the longitudinal edges of the lid 24 and engage the side walls of the case. To position the lid 24 the bars 31 are moved at right angles to the longitudinal edges of the lid 24 and 50 into engagement with the upper edges of the side walls of the case. Upon the depression of the hooks of the spring catches 26 and 27 and the sliding of the catches so that the hooks will engage the cross over plates 55 29, the lid is securely locked in position.

A transverse bar or rod 33 is secured upon the under face of the lid 24 centrally of the end edges thereof and is provided with downwardly extending right angular lugs 60 34 which are designed to coöperate with loops or rings 35 that are secured to the center bars 7 of the side walls upon the interior of the box or receptacle. The rings or loops 35 receive the downwardly directed lugs or 65 ends of the rod 33 and provide rigidity for

the structure as well as to securely hold the lid or cover against derangement relative to the receptacle. This construction strengthens the case and does not interfere with the packing of material to be shipped therein. 70

When the case has been emptied and is ready to be collapsed the cover, fillers, and partitions 30 and bottom are removed. Then the side walls are swung toward each other by being moved longitudinally in opposite 75 directions.

The end walls 2 and 3 swing into parallel relation to one another, and the walls 1 and 4 swing into another plane parallel to the first mentioned plane, and the top, bottom, partitions and fillers may be positioned between the side walls and securely tied in position. It is apparent that when the case is collapsed it occupies very little space and therefore may be conveniently stored or transported. 85

While I have shown and described the preferred embodiment of my invention, it will be understood that minor changes in construction, combination, and arrangement of parts may be made without departing from 90 the spirit and scope of the invention as claimed.

Having thus described my invention, I claim:

1. A collapsible case comprising a pair of 95 side walls including skeleton frames, a pair of end walls having skeleton frames, the upper and lower bars of said first mentioned frames projecting across the upper and lower bars of the second mentioned 100 frames, U-shaped corner rods connecting the meeting ends of the frame bars and cutting diagonally across the corners of the case, a rigid bottom and supporting plates carried by the side and end walls to removably retain the bottom within the case in engagement with the inner faces of the walls.

2. A collapsible case comprising a pair of 110 side walls, a pair of end walls, the side and end walls each including a skeleton frame having upper and lower bars, the upper and lower bars of the end walls having their outer longitudinal edges notched adjacent their terminals to receive the extremities of the upper and lower bars of the end walls, 115 a U-shaped fastening rod at each corner of the case, the arms of said rods being extended through the upper and lower bars of the walls, and the central portions of the fasteners cutting diagonally across the corners 120 of the case, a rigid bottom and supporting plates secured to the walls and extending into engagement with the lower surface of the bottom to hold said bottom removably within the case.

3. A collapsible case comprising bottom, side and end walls, a lid to coöperate with the bottom, side and end walls, transverse bars secured at the ends of said lid upon the outer face thereof, spring catches slid able 130

between the bars and lid having inwardly turned terminals forming hooks at their outer ends, said end walls having recesses at their upper edges, cross over plates bridging said recesses, said spring catches designed to coöperate with said cross over plates and a pair of bars pivoted between said first named bars and said lid and arranged to extend beyond the longitudinal

edges of said lid and engage the side walls 10 of said case.

In testimony whereof I affix my signature in presence of two witnesses.

WILLIAM E. PEYTON.
